UNITED STATES PATENT OFFICE

94,926

DESIGN FOR AN AIRPLANE

Igor I. Sikorsky, Nichols, Conn., assignor, by
mesne assignments, to Sikorsky Aircraft Cor-
poration, a corporation of Delaware

Application May 19, 1934, Serial No. 51,850

Term of patent 7 years

To all whom it may concern:

Be it known that I, Igor I. Sikorsky, a citizen
of the United States, residing at Nichols, in the
county of Fairfield and State of Connecticut,
have invented a new, original, and ornamental
Design for an Airplane, of which the following
is a specification, reference being had to the ac-
companying drawing, forming part thereof.

Figure 1 is a top plan view of my design.

Figure 2 is a front elevation thereof.

Figure 3 is a side elevation.

Figure 4 is a top perspective view.

Figure 5 is a bottom perspective view.

I claim:

The ornamental design for an airplane as
shown.

IGOR I. SIKORSKY.
